FIG. 1.

FIG. 3.

FIG. 2.

Inventor

Truman S. Fowler.

UNITED STATES PATENT OFFICE

TRUMAN STEVES FOWLER, OF BOOTHBAY HARBOR, MAINE

DESIGN FOR AN ASH TRAY

Application filed July 3, 1931. Serial No. 40,410. Term of patent 7 years.

To all whom it may concern:

Be it known that I, TRUMAN S. FOWLER, a citizen of the United States, residing at Boothbay Harbor, in the county of Lincoln and the State of Maine, have invented a new, original, and ornamental Design for an Ash Tray, of which the following is a specification, reference being had to the accompanying drawings, forming part thereof.

The use of the fluted fins as shown in Figure 3, as cigarette and cigar rests, is an exclusive feature of this ash tray design.

I claim:

The ornamental design for an ash tray, as shown and described.

TRUMAN S. FOWLER.
